MATAJIRO KAWAMORI, OF KWANTO-SHU, JAPANESE LEASED TERRITORY IN CHINA

AUTOMATICALLY-INKING NUMBERING MACHINE

Application filed October 14, 1929. Serial No. 399,630.

This invention relates to improvements in or relating to numbering machines, more particularly automatically inking numbering machines and has for its object to provide an automatically inking numbering machine, simple in construction and speedy in service.

In accompanying drawings:

Fig. 1 is a perspective view of a machine embodying the invention.

Fig. 2 is a vertical section of machine.

Fig. 3 is another vertical section of the machine.

Referring to the drawings, 1 is the machine frame of substantial U-shape and is formed with an upstanding cylindrical housing 2 for a spring 3. 4 is the base having a central opening 5 and is attached to end of the side-limbs of said machine frame by suitable means, such as the screws 6, 6. 7 is substantially U-shaped movable frame having a bored spindle 8 and is slidably inserted into guide ways 9, 9 formed at inside of the side-limbs of the machine frame, outwardly extending said spindle through the housing 2, as seen in Fig. 2. Attached to outer end of the spindle 8 is an operating handle knob 10 having the pendent housing 11 for receiving the upper end of the spring 3 in telescopic relation to the housing 2, so that the frame 7 is normally held upward with its top against the inner side of the top of the machine frame 1 by means of the spring 3 while it may be pressed down against the spring by means of the operating handle knob 10. 12 is secondary substantially U-shaped movable frame having a spindle 13 and longitudinal slots 14, 14 formed at the side-limbs for hereinafter described purpose and is slidably inserted into guide ways 15, 15 formed at inside of the side-limbs of the frame 7, outwardly extending said spindle through the bore of the spindle 8, as seen in Fig. 2. Attached to outer end of the spindle 15 is a press button 16 movable in the cavity 17 formed on the handle knob 10. A spring 18 is arranged in the cavity 17 against the under side of the press button 16 at its upper end, so that the secondary movable frame 12 is normally

held upwards with its top against the inner side of top of the first movable frame 7 by means of the spring 18 while it may be pressed down against said spring by means of the press button.

A number of the shifting wheels 20 are mounted on a shaft 19 transversely secured to the side-limbs of the first mentioned movable frame 7 and consecutively arranged one after the other between the collars 21, 21 secured to the shaft. Said shifting wheel is provided with a lever 22 and formed with teeth through about a half of its circumference and a notch 23 at the teeth end opposite to the lever. A spiral spring 24 is arranged in the housing 25 formed on one side of the shifting wheel for that purpose, one end of which is secured to the shifting wheel while the other end is secured to the shaft 19, so that the spring always tends to maintain the shifting wheel in its normal position as shown in Fig. 3. The shift wheel 20 is also provided with a sector opening 26 diametrically opposite to the teeth and having a series of grooves 27 on its inner circumference. A number of the headed pins 28, one for each shift wheel, are arranged in the cavities 29 provided in the bar 30 transversely secured to the secondary frame 12, extending upwardly the shank of said pin through the hole of a diameter smaller than the internal diameter of the cavity formed in the top of said cavity, the head of the pin being located in the cavity and pressed upwardly by means of the spring 31 arranged in the cavity between the head of the pin and a bottom cover 32 of the cavities secured to the bottom side of the bar 30, so that the end of the pin 28 may be engaged with the grooves 27 to hold the shift wheel 20 in the desired position. The engagement of the pin 28 and the grooves 27 is such that the shift wheel 20 may be rotated by moving downward the lever 22 against the spring 24, the pin being allowed to get out the grooves against the spring 31. The spring 24 is not sufficient to cause the pin to get out the groove against the spring 31, while it is sufficient to rotate the shift wheel when the pin is kept out of the grooves by pressing

down the secondary frame 12 by means of the press knob 16 to move downward the bar 30 carrying the pins.

A number of electrotype wheels 33, each of which bears numerals 0 and 1 to 9 inclusive and has a pinion 34 formed integrally with it for meshing the teeth of the shift wheel 20, are rotatably mounted on a shaft 35 transversely secured to the side-limbs of the first movable frame 7 and consecutively arranged one after the other between the collars 36, 36 secured to said shaft, respective pinion meshing the teeth of corresponding shift wheel. The pinion 34 is formed with a stop piece 37 to engage with shoulder of the notch 23 of the shift wheel 20 when the electrotype wheel is in normal position, as shown in Fig. 3. The ink pad 38 is held in position spaced a short distance from the bottom face of the electrotype wheels by means of the links 39, 39 and 40, 40 connected thereto. The links 39, 39 are longer than the links 40, 40 and the upper end thereof is connected to the secondary movable frame 12, while the upper end of the links 40 is connected to the machine frame 1, so that the ink pad 38 will be turned up to clear up way of the electros when the secondary movable frame 12 is moved fully downward by means of the press button 16. 41 is the casing attached to the machine frame 1 and is provided with a number of slots for the passages of the levers 22 of the shift wheels 20 and having marks to indicate positions of the levers corresponding to the electros in printing position.

In operation, at first the electros are set to represent desired number by means of the levers 22 and then both the operating handle knob 10 and the press button 16 are pressed down together, thereby the electro will at first press the ink pad to be inked up and then will print on the paper placed under the base 4 through the opening 5 thereon, the ink pad being turned out of way of the electros. Thus, the printing of the same number may speedily be repeated. To restore the electrotype wheels to their normal position, the press button 16 is pushed and said wheels will be rotated by the spring 24 to their normal position, and now will be ready for reset of new numbers, the pins 28 disengaging from the grooves 27 due to down motion of the secondary movable frame 30.

Having now particularly described and ascertained the nature of my said invention and in what manner the same is to be performed, I claim:

1. An automatically inking numbering machine comprising a substantially U-shaped machine frame having a top housing for a spring, a base having a central opening, a substantially U-shaped movable frame having a bored spindle with an op-

erating handle knob on its upper end, a secondary substantially U-shaped movable frame having a spindle with a press button on its upper end upwardly extending through said bored spindle, a number of shifting wheels mounted in said first mentioned movable frame by means of a shaft and spiral springs and having the teeth engaging a pinion, a lever for manual operation, a sector opening with a series of internal grooves and a notch adapted to engage a stop piece of the pinion in its normal position, a bar transversely secured to said secondary movable frame and carrying a number of pins adapted to engage said grooves under spring tension, a number of electrotype wheels rotatably mounted in the first mentioned movable frame, each having a pinion engaging the teeth of said shifting wheel and an ink pad mounted below said electrotype wheels by means of links from said secondary movable frame and said machine frame, as described and shown.

2. An automatically inking numbering machine as claimed in claim 1, in which the internal grooves in the sector opening of the shifting wheel cooperate with the pins carried by the bar transversely secured to the secondary movable frame to maintain said shifting wheel in its adjusted position.

3. An automatically inking numbering machine as claimed in claim 1, in which the shifting wheels are loosely mounted on a bar transversely secured to the movable frame and are connected thereto by means of the spiral spring, each being connected at ends to said shifting wheel and bar respectively, so that said shifting wheels will return from their adjusted position to their normal position on release of the pin from the internal grooves in the sector opening thereof by lowering the secondary movable frame by pushing the push button secured on upper end of its spindle.

4. An automatically inking numbering machine as claimed in claim 1, in which the movable frame and the secondary movable frame will be operated by pushing both the push button and the handle knob when printing any desired number, while the secondary movable frame only will be operated when returning the adjusted electrotype wheels to their normal position.

In testimony whereof I affix my signature.
